United States Patent Office

Des. 181,502
Patented Nov. 19, 1957

181,502

COMBINED PICTURE FRAME AND CLOCK

Joseph Steg, Brooklyn, N. Y., assignor to Guild Crest Corporation of America, Jersey City, N. J., a corporation of New Jersey

Application March 20, 1957, Serial No. 45,344

Term of patent 3½ years

(Cl. D29—20)

Fig. 2.

Fig. 1 is a front elevational view of a combined picture frame and clock, showing my new design;

Fig. 2 is a top plan view;

Fig. 3 is an end elevational view of the same.

I claim:

The ornamental design for a combined picture frame and clock, as shown.
